UNITED STATES PATENT OFFICE

119,591

DESIGN FOR A GAME APPARATUS

Jerry C. Koci, Chicago, Ill., assignor to Chicago
Coin Machine Mfg. Co., Chicago, Ill., a corporation of Illinois

Application January 17, 1940, Serial No. 89,527

Term of patent 14 years

To all whom it may concern:

Be it known that I, Jerry C. Koci, a citizen of the United States, and a resident of Chicago, in the county of Cook and State of Illinois, have invented a new, original, and ornamental Design for a Game Apparatus, of which the following is a specification, reference being had to the accompanying drawing forming a part thereof, and in which the single figure is a perspective view of a game apparatus showing my new design.

I claim:

The ornamental design for a game apparatus, as shown.
